UNITED STATES PATENT OFFICE.

HAMILTON F. LOW, OF NEW YORK, N. Y.

DISH-WASHING APPARATUS.

No. 858,522.

Specification of Letters Patent.

Patented July 2, 1907.

Application filed January 15, 1906. Serial No. 296,187.

To all whom it may concern:

Be it known that I, HAMILTON F. Low, a citizen of the United States, residing at the borough of Manhattan, city, county, and State of New York, have invented new and useful Improvements in Dish-Washing Apparatus, of which the following is a specification.

This invention relates to dish washing apparatus, and has for its object to provide improved apparatus of this character which will be superior in point of efficiency, 10 durability and economy, and safety in operation.

The invention has for its particular object the provision of apparatus of the character described, whereby the cleansing water may be caused to execute a highly efficient to and fro movement above and throughout the 15 pile or load of dishes to be washed, at the same time in the main being directed downwardly upon the dishes so as to prevent disarrangement of the same, with the attendant breakage or fracture, during the washing operation.

20 In the drawings: Figure 1 is a front elevation of a dish washing apparatus constructed according to the invention; Fig. 2 is an enlarged vertical transverse sectional view of tank 1, taken upon the line *a—a*, Fig. 1, and looking in the direction of the appended arrow; Fig. 3 is a 25 substantially horizontal transverse sectional view of the same, taken upon the lines *b—b*, Fig. 2, looking in the direction of the appended arrow; and, Fig. 4 is a perspective view of a diffusion element constituting an essential part of the invention.

30 Corresponding parts in all the figures are denoted by the same reference characters.

Referring with particularity to the drawings, the invention is illustrated as being comprised within two assembled casings or tanks, 1 and 2, used respectively for 35 washing and rinsing. While but one of the washing tanks 1 is shown, a number of the same may be employed, said tanks being arranged in a battery, and being duplicates in formation and provision of operative parts, and being used, in practice, for the initial washing 40 operation. Without reference to the number of the tanks 1, but one of the rinsing tanks 2 is required for the final rinsing operation.

Each of the tanks, 1 and 2, is provided at its lower forward portion with an inlet header 3, and connected 45 with both of said headers is a steam supply pipe 4 and a water supply pipe 5, cocks 6 and 7 respectively being installed between the steam supply pipe 4 and the headers 3 and between the water supply pipe 5 and the headers 3.

50 Each of the tanks 1 and 2 is provided at its upper forward portion with an overflow header 8, which headers are connected by an overflow pipe 9, which is extended downwardly, as at 10, and horizontally beneath the tanks, to form a discharge pipe 11, communicating with 55 discharge pipes 12, one of which connects with the bottom portion of each of the tanks. Each of the discharge

pipes 12 is controlled, in its communication with the portion 11, by a cock 13.

The bottom of each of the tanks 1 and 2 is provided with a bottom 14 which includes a screened orifice 15 60 communicating with the respective discharge pipe 12.

Each of the tanks 1 and 2 is preferably four-sided, and each of the corners of the same, at the bottom of the tank, is separately cut off by two upright partitions 16 which approach each other inwardly at an acute angle 65 and are but slightly spaced apart at their adjacent outer edges. Each couple of these partitions 16 forms, in the respective corner 16^a, a pocket into which the water in the tank flows in its circulation through the tank. Resting upon the several pairs of partitions 16, is a grating or 70 perforated detachable partition 17 which extends across the tank but slightly above the bottom 14 thereof, the grating 17 being also provided with or superposed upon an annular plate 18 directly beneath which, and above the bottom 14, is arranged an agitator 19, comprising a 75 plurality of curved blades fixed to an upright shaft 20 journaled in a bearing 21 fixed to the bottom 14, said shaft projecting beneath the bottom 14 and being provided with a pulley 22 whereby it may be operated. The agitator 19 operates in an agitation chamber 80 between the grating 17 and base 14, and said agitator is so formed in the proportioning of its plates, as to draw the water downward through the grating 17 from the interior of the tank.

At each of its four sides, each tank is provided with a 85 fixed or detachable diffusion element 23, which said element consists of an upright plate 24 ranging downwardly within the tank slightly divergently from the respective side thereof, from a point just beneath the plane of the overflow header 8 to the plane of the corner partitions 90 16. Each of these plates 24 is provided with side members 25 which closely engage with the respective sides of the tank, and each of said plates is preferably detachably connected with the respective side of the tank, at its upper portion, by means of a screw or bolt 26. 95

Each of the plates 24 is provided with two or more transverse series of elongated openings 27, the openings of each series being preferably arranged in a slight curvature, and above each series of openings is arranged a transverse baffle 28 extending between the side members 25. The baffles 28, when the diffusion elements 23 are in place, extend obliquely downwardly towards the sides of the tanks, and the openings 27 are formed with substantially the same oblique downward range.

The operation, method of use and advantages of the 105 improved washing machine embodying the invention will be readily understood from the foregoing description taken in connection with the accompanying drawing and the following statement.

When steam and water are simultaneously admitted 110 to the headers 3, and from these headers the steam and water flows into the tanks, and behind two of the diffu-

sion elements 23 in the tank or tanks 1, whence the heated water is directed by the baffles 28 and through the openings 27 downwardly upon the dishes which are placed upon the grating 17. At the same time, if the 5 shaft 20 is operated by the pulley 22, the agitator 19 draws the water downwardly through the several openings 27 from the spaces behind the several diffusion elements 23, the water passing inwardly through said openings and downwardly onto the dishes. The water is 10 also forced into the pockets in the corners of the tanks whence it issues through the spaces between the partitions and joins in the general condition of agitation of the water within the tanks. It will be understood that the operation in each of the washing tanks employed is 15 the same. It results from the peculiar arrangement of the diffusion elements 23, the inlet of the first water into the tank behind one of the diffusion elements 23, and the combination of such diffusion elements with the agitator 19 and the partitions 16, in part or in whole from 20 such arrangement and combination, that a condition of agitation is instituted within the tank, when the flow of water and agitation of the same is set up, which is accomplished by an ebullition of the water within the tank in a general downward and upward as well as criss- 25 cross or to and fro movement. The downward movement of the water keeps the dishes firmly seated upon the grating 17, and the to and fro or crisscross movement of the water effectually dislodges from the dishes any material sticking thereto. The overflow pipe 9 and dis- 30 charge pipe 11, through the headers 8 and discharge pipes 12, permit of effectually draining the tanks and preventing overflow of the same.

The entire apparatus is very positive and efficient in operation and comparatively simple and inexpensive in 35 construction, in view of its efficiency; and its particular point of advantage consists of the highly efficient results in operation obtained from the peculiar arrangement and combination of parts and members causing the downward and upward and crisscross circulation of 40 the cleansing currents.

I do not desire to be understood as limiting myself to the particular construction of parts and members as described and illustrated, but reserve the right to vary the same, in adopting the improvements to varying condi-

tions of use, without departing from the spirit of invention or the scope of the following claims. 45

Having thus described my invention, I claim and desire to secure by Letters Patent:

1. A dish washing apparatus comprising a casing, a diffusion element therein, a supply pipe for delivering fluid 50 to said casing behind said element and agitating means in the casing independent of the diffusion element.

2. A dish washing apparatus comprising a casing, diffusion elements arranged at the sides of the casing, inlet pipes for supplying fluid to the casing behind one of said 55 elements and an agitator located in the bottom of the casing independent of the diffusion elements.

3. A dish washing apparatus comprising a casing, a diffusion element consisting of a perforated plate arranged at one side of the casing, inlet pipes for delivering 60 fluid between said plate and the side of the casing and agitating means in the bottom of the casing.

4. Improved apparatus of the character described, comprising a casing provided at its corners with angularly approaching spaced partitions forming pockets, a grating 65 supported upon said partitions and forming an agitator chamber, an agitator arranged within said chamber, and diffusion elements arranged within said casing.

5. In improved apparatus of the character described, a casing, and a diffusion element arranged within the casing 70 and consisting of a plate connected with and spaced from one side of the casing and provided with a feed opening and an obliquely downwardly extending baffle arranged adjacent to said feed opening.

6. In apparatus of the character described, a casing, 75 and a diffusion element consisting of a plate connected with and spaced from one side of said casing and extending downwardly and divergently from said side within said casing, said plate being provided with side members contacting with said side of said casing and being further 80 provided with a feed opening and with a downwardly ranging baffle arranged above said feed opening.

7. In apparatus of the character described, a casing, and a diffusion element consisting of a plate connected with and spaced from one side of said casing and extending 85 downwardly within said casing divergent to said side of said casing, said plate being provided with two feed openings in superposed relation and with a baffle arranged above each of said feed openings, said baffles and said feed 90 openings ranging obliquely downwardly.

In testimony whereof I have signed my name to this specification in the presence of two subscribing witnesses.

HAMILTON F. LOW.
